Primary Examiner — Cynthia Ramirez*(74) Attorney, Agent, or Firm* — Fross Zelnick Lehrman & Zissu P.C.; Charles T. J. Weigell Esq.; Lawrence E. Apolzon Esq.(57) **CLAIM**

The ornamental design for a suitcase carrier, as shown and described.

DESCRIPTION

FIG. 1 is a front perspective view of a suitcase carrier showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a rear view thereof;

FIG. 8 is a front perspective view of the suitcase carrier shown in an open position;

FIG. 9 is a front view thereof;

FIG. 10 is a rear view thereof;

FIG. 11 is a left side view thereof;

FIG. 12 is a right side view thereof;

FIG. 13 is a top view thereof; and,

FIG. 14 is a bottom view thereof.

The broken line of the portion of the base of the suitcase carrier forms no part of the claimed design.
